UNITED STATES PATENT OFFICE.

EDWARD H. SCHWARTZ, OF CHICAGO, ILLINOIS, ASSIGNOR TO THE HAWLEY DOWN DRAFT FURNACE COMPANY, OF CHICAGO, ILLINOIS, A CORPORATION OF ILLINOIS.

FURNACE.

No. 871,070.

Specification of Letters Patent.

Patented Nov. 12, 1907.

Application filed January 16, 1903. Serial No. 139,312.

To all whom it may concern:

Be it known that I, EDWARD H. SCHWARTZ, residing at Chicago, Cook county, Illinois, have invented certain new and useful Improvements in Furnaces, of which the following is a specification.

My invention relates to certain new and useful improvements in furnaces of the same general character or class as the furnace described and claimed in my prior Patent No. 708,782 dated September 9, 1902.

10 The features of novelty and utility of my present furnace will be understood from the description hereinafter given.

In the drawings, Figure 1 is a central vertical and longitudinal section of my furnace; Fig. 2 a cross section thereof and Fig. 3 a sectional plan view on line A—B of Fig. 1.

15 The furnace comprises essentially a furnace body or shell mounted to tilt on suitable standards and forming a furnace chamber, in combination with burners 20 for directing in a peculiar manner a gaseous flame (or the like) into the furnace chamber, the air which is mixed in such burner being preliminarily heated by the waste heat of the furnace.

As herein shown, the furnace is in the form of a cylinder from which extend truncated conical ends and consists of a cylindrical shell 1 and ends 2 and 3, of boiler plate or the like, which is lined with fire brick 4 or other suitable refractory material, although the hearth 5 may be made of ganister or the like.

25 The furnace has a top outlet 6 and end openings 7 and 8, the latter opening being intended as a pouring or tap opening and therefore not as large as the opposite opening 7 which is intended as a charging opening. However, the construction shown and just described is merely designed to illustrate the preferable form of furnace, and it is evident that either of the two openings may be used as a pouring opening or a discharge opening, and also that a single opening may, in some constructions or sizes of furnace, be 30 used as a combined charging and pouring opening, so far as the other features of my invention are concerned. The openings 7 and 8 are closed by doors 9 and 10 respectively, which are of the usual and well known construction.

40 Upon the shell or body of furnace are arranged or bolted trunnions 11 and 12, bearing in the standards or frames 13 and 14. Suitable actuating mechanism, as shown in my prior Patent No. 725,490, issued April 14, 1903, co-operates with the trunnion 11 to 45 cause tilting of the furnace, such mechanism comprising a worm gear 15 fixed to the trunnion and operated by the hand wheel 16 through the medium of the worm gear 17.

The trunnion 12 is a hollow one with an air opening

18 communicating with the burners through a pipe 19 55 and with a source of air pressure through a stationary air supply pipe 20. An oil or fuel supply pipe 21, extending to the burners, is swiveled onto the air supply pipe 20, in the same manner as shown in my said prior Patent No. 725,490, and consequently detailed description of these particular parts is unnecessary.

The outlet 6 is extended beyond the surface of the furnace by a cylindrical extension 22 made of plate and lined with fire brick. This extension piece and its 65 lining, as well as the lining of the furnace immediately adjacent the outlet opening, are made removable for the purpose of permitting ready renewal of these particular linings, which are the ones subjected to the greatest wearing action. This shell extension 22 is 70 surrounded by a concentric shell 23, so as to form an annular air heating chamber 24 closed at its top, and communicating with the air pipe 19 as shown in Figs. 2 and 3.

75 The burners 25, two in number in the present instance, enter the top of the furnace on either side of the outlet opening and are inclined towards each other in such manner as to direct, into the furnace chamber, flames which converge or meet substantially at the central point of the furnace and form two 80 rotary flames on either side of the central vertical axis of the furnace, all as illustrated in a general way by the dotted lines in Figs. 1 and 2.

In detail, the burners each comprise a casting having a nozzle portion 26 penetrating the furnace and also a 85 lateral portion 27 communicating with the air heating chamber 24 and bolted or otherwise removably secured to the shell or casing of such chamber (see Fig. 1), with the result that the entire air heating chamber and the outlet extension itself can be removed without disturbing the burners. The fuel is supplied through injectors 28 secured to the burners and extending axially of their nozzles. These injectors, which are governed by the hand valves 29, receive oil from the branch pipes 30 communicating with the oil supply pipe 21. 95

In operation, the material to be melted or otherwise treated is introduced into the furnace, preferably after a preliminary heating, and the burners are then started, with the result that the rotating flames hereinbefore described rapidly melt or reduce such material lying 100 upon the bottom or hearth of the furnace. During this period the charging opening and pouring opening are both closed by their doors, and the flames and products of combustion pass outward through the outlet 6 and the outlet extension, thereby heating the latter and 105 causing a heating of the air in chamber 24 before introduction to the burners, so that a hotter and better flame is produced. At the proper time, the furnace is tilted

and the molten material poured through the top or pouring opening 8, which has been opened for this purpose.

In some operations, particularly that of smelting, the furnace may be tilted to such extent that the charging opening approaches the vertical and such furnace may thereupon be charged with the proper amount of ore and their fluxes. After the furnace is restored to its normal or desired working position, the ore will remain considerably banked up toward the right end of the furnace chamber, Fig. 1, with the main body above the hearth, with the resulting advantage that the ore if better exposed to the flame and, as melted, will run down upon the hearth. The molten material thus flowing to the hearth in comparatively thin streams will be highly heated by the flames and rendered quite fluid. However, this particular method of melting is applicable to the melting of metals as well as of ores and also to the melting and treatment of other substances.

The construction of the furnace and the arrangement 20 of the burners therein are such that the flames will take the directions indicated in the drawings. The two flames will converge centrally of the furnace and because of the general direction of the flames, after converging, which is downwardly, directly and squarely 25 against the hearth, and because also of the upward curvature of the opposite ends of such hearth, the flame will divide into two portions, one rotating or moving toward one end of the furnace and the other toward the other end thereof. As the upper end walls of the furnace are downwardly inclined, the flames will be doubled back and caused to rotate in the furnace before 30 exit therefrom. This described rotation of the flames is also brought about by the arrangement of the outlet substantially at the center of the furnace.

35 My furnace may be employed for many different purposes and for the treatment of different materials, whether metals, ores, or not, and I therefore contemplate using the furnace wherever applicable, whether the operation be metallurgical, as herein described, or not; for instance, my furnace may be used for the melting of glass, enamel and other non-metallic materials.

I claim:

1. A furnace comprising a tiltable body and burners discharging into the furnace flame jets which converge and are combined into a single flame, such flame being directed towards and arranged to impinge the hearth of the furnace and the walls of such furnace being arranged to divide the flame into separate flames and to cause the same to move laterally towards opposite ends of the furnace.

2. A furnace comprising a tiltable body and burners discharging flame into the furnace, the flame being directed towards the hearth of the furnace and the walls of such furnace being arranged to cause the flame to rotate in a vertical plane in two similar circles.

3. A furnace comprising a tiltable body and burners discharging flame into the furnace, the burners being convergently arranged and the flame being directed towards the hearth of the furnace which is arranged to divide such flame into two rotating flames.

4. A furnace comprising a tiltable body providing a chamber having a cylindrical central portion and a truncated conical end, and burners arranged convergently in the top of the furnace and arranged to project flame towards the hearth of the furnace, said conical end of the furnace causing the flame to rotate.

5. A furnace comprising a tiltable body having a top outlet for the products of combustion, and burners entering the furnace on either side of the outlet and discharging flame into the furnace, the interior walls of the fur-

nace being arranged to cause the flame to rotate in the furnace in two similar circles before exit through the outlet.

6. A furnace comprising a tiltable body having a top outlet for the products of combustion, and burners entering the furnace on either side of the outlet and arranged convergently whereby the flame jets therefrom converge or focus at a point below such outlet, the combined flame jet being directed towards the hearth of the furnace which is arranged to divide such flame into two flames rotating on either side of such focal point. 75

7. A furnace comprising a tiltable body having end openings for charging and pouring respectively and also having a top opening for products of combustion, and burners located on either side of the top opening and arranged to discharge flame towards the hearth of the furnace, the interior walls of the furnace being arranged to cause the flame to rotate before exit through the top opening. 80

8. A furnace comprising a tiltable body having an outlet and provided with an extension communicating with the outlet, a casing forming an air heating chamber around said extension, an air supply pipe communicating with said chamber, burners arranged in said furnace and communicating with and receiving heated air from said chamber, and a fuel pipe for supplying fuel to said 90 burners. 95

9. A furnace comprising a furnace body provided with openings at opposite ends for charging and pouring respectively and also provided with a vent opening, and burners discharging flame into the furnace and so inclined as to cause the flame to impinge the hearth, said hearth being inclined over its central portion upwardly to cause the flame to move laterally toward opposite ends of the furnace. 100

10. A furnace comprising a furnace body substantially barrel-shaped and provided with openings at opposite ends for charging and pouring respectively and also provided with a vent opening at the upper or longer side of said body, and burners entering the furnace body at a point adjacent said vent opening and discharging flame into the furnace the longer axis of the furnace body being substantially horizontal. 105

11. A furnace comprising a furnace body substantially barrel-shaped and provided with openings at opposite ends for charging and pouring respectively and also provided with a vent opening, and a burner entering the furnace body at a point adjacent said vent opening and discharging flame into the furnace the longer axis of the furnace body being substantially horizontal. 110

12. A furnace comprising a tiltable furnace body provided with openings at opposite ends for charging and pouring respectively and also provided with a vent opening, and a burner for discharging flame into the furnace the longitudinal or horizontal axis of the furnace exceeding its transverse axis. 115

13. A furnace comprising a tiltable furnace body provided with openings at opposite ends for charging and pouring respectively and also provided with a vent opening, said furnace body having a hearth upwardly inclined at its ends, and burners discharging flame into the furnace toward the middle point of the hearth and arranged within the vertical planes of such ends. 120

14. A furnace comprising a furnace body provided with openings at opposite ends for charging and pouring respectively and also provided with a vent opening, said furnace body having a hearth upwardly inclined at its ends, being substantially barrel-shaped with the longer axis substantially horizontal and a plurality of burners convergently arranged to direct flame toward the middle point of the hearth. 125

15. A furnace comprising a tiltable furnace body having a barrel-shaped chamber with inclined ends forming a hearth, whose ends are inclined toward the middle portion and burners convergently arranged to direct the flame towards the central portion of the hearth, said inclined ends of the hearth being arranged to divide said flame into two separate and rotating flames. 130
